(57) **CLAIM**

The ornamental design for a tire, as shown and described.

DESCRIPTION

FIG. 1 is a front right perspective view of a first embodiment of a tire showing our new design, the design repeated about the circumference of the tire;

FIG. 2 is a front elevation view thereof, the design repeated about the circumference of the tire;

FIG. 3 is a right elevation view thereof, it being understood that the right elevation view is identical thereto;

FIG. 4 is a partial sectional view taken along line 4-4 in FIG. 2;

FIG. 5 is a front right perspective view of a second embodiment of the tire showing our new design, the design repeated about the circumference of the tire;

FIG. 6 is a front elevation view thereof, the design repeated about the circumference of the tire;

FIG. 7 is a right elevation view thereof, it being understood that the right elevation view is identical thereto; and,

FIG. 8 is a partial sectional view taken along line 8-8 in FIG. 6.

It being understood that the dashed lines in FIGS. 5, 6, 7, and 8 form no part of the claimed design and that the dot-dash line shown in FIGS. 5, 6 and 7 represents a boundary line, matter radially inside of which is not claimed.
